The ornamental design for a label printer, as shown and described.

DESCRIPTION

FIG. 1 is a front, top and right side perspective view of a first embodiment of a label printer showing my new design; FIG. 2 is a rear, top and left side perspective view thereof; FIG. 3 is a front view thereof; FIG. 4 is a rear view thereof; FIG. 5 is a top plan view thereof; FIG. 6 is a bottom plan view thereof; FIG. 7 is a right side view thereof; FIG. 8 is a left side view thereof; FIG. 9 is a front, top and right side perspective view of a second embodiment of a label printer showing my new design; FIG. 10 is a rear, top and left side perspective view thereof; FIG. 11 is a front view thereof; FIG. 12 is a rear view thereof; FIG. 13 is a top plan view thereof; FIG. 14 is a bottom plan view thereof; FIG. 15 is a right side view thereof; and, FIG. 16 is a left side view thereof. The broken lines immediately adjacent to the shaded areas and defining unshaded regions depict the bounds of the claimed design, while all other broken lines are directed to the environment. The broken lines form no part of the claimed design.
